UNITED STATES PATENT OFFICE

117,680

DESIGN FOR AN ILLUMINABLE HOLDER FOR PICTURES OR THE LIKE

Theophile A. Stiffel, Chicago, Ill.

Application July 17, 1939, Serial No. 86,057

Term of patent 3½ years

To all whom it may concern:

Be it known that I, Theophile A. Stiffel, a citizen of the United States, residing at Chicago, in the county of Cook and State of Illinois, have invented a new, original, and ornamental Design for an Illuminable Holder for Pictures or the like, of which the following is a specification, reference being had to the accompanying drawing, forming part thereof.

In the drawing,

Fig. 1 is a front elevational view of the illuminable holder for pictures or the like, showing my new design, the opposite side being substantially like that shown;

Fig. 2 is a side elevational view thereof.

I claim:

The ornamental design for an illuminable holder for pictures or the like, as shown and described.

THEOPHILE A. STIFFEL.
